UNITED STATES PATENT OFFICE.

JAMES McGILLIS, OF CHIPPEWA FALLS, WISCONSIN.

TRACTION-SLED.

No. 808,565.

Specification of Letters Patent.

Patented Dec. 26, 1905.

Application filed February 21, 1905. Serial No. 246,759.

To all whom it may concern:

Be it known that I, JAMES McGILLIS, a citizen of the United States, residing at Chippewa Falls, in the county of Chippewa and State of Wisconsin, have invented a new and useful Traction-Sled, of which the following is a specification.

This invention relates to sleds, and has for its object to provide improved traction means for mechanically propelling the sled, and in this connection to have the sled mounted upon fixed runners and to employ other movable runners, and to impart stepping movements thereto for engagement with a road-bed to propel the sled by the advance movement of the movable runners.

Another object of the invention is to effect the proper elevation of the moving runners when being advanced to a new position upon the road-bed, and to cushion the impact of the movable runners with the road-bed, so as to obviate violent pounding and consequent damage to the moving runners and other parts of the operating mechanism.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a plan view of the sled-propelling mechanism of the present invention, the body of the sled being indicated in dotted lines. Fig. 2 is a detail longitudinal sectional view taken through the sled-propelling mechanism, showing in full lines one of the moving runners in its depressed active position and in dotted lines another runner in an elevated inactive position. Fig. 3 is a cross-sectional view of the sled-propelling mechanism. Fig. 4 is a detail sectional view showing in full lines the active position of one of the runners and in dotted lines an elevated position.

Like characters of reference designate corresponding parts in each and every figure of the drawings.

The present sled includes a bed or platform 1, which is supported at its rear end by a pair of fixed runners 2, there being any or-

inary or preferred form of bob 3, pivotally mounted upon the front end portion of the under side of the bed or platform and having a hand-wheel 4 or other suitable means for turning the bob to steer the sled. The form 60 of the bob is immaterial to the present invention, and therefore may be varied at will.

The propelling mechanism of the present invention includes a pair of movable runners 5 for each stationary runner, said moving 65 runners being located at each side of the adjacent stationary runner and working in substantial parallelism therewith.

For the support of each pair of runners there is a pair of shafts, (designated 6 and 7,) 70 which are suitably journaled, as at 8 and 9, upon the adjacent stationary runner. The shaft 6 is provided with a crank-bend 10 at the inner side of each stationary runner and a terminal crank 11 at the outer side of said 75 runner, while the shaft 7 is provided with similar cranks 12 and 13. Connection is had between each movable runner and each adjacent crank by means of a spring link or bar 14, the forward end of which is fixed to the 80 top of the runner by one or more fastenings 15, from which the spring-link is inclined or bowed upwardly and rearwardly with its upper free end terminating in a loop or eye 16, loosely embracing the adjacent crank, whereby 85 the movable runner is worked back and forth by the movement of the crank. The members of each pair of inner and outer cranks are disposed opposite one another or at one hundred and eighty degrees, whereby 90 when one movable runner is moving forwardly the other is moving rearwardly, and vice versa, wherefore it will be understood that a stepping movement is imparted to the movable runners. For each spring-link 14 95 there is an upstanding guide member 17, rising from the adjacent movable runner and in the form of an arch straddling the link, so as to prevent lateral strains thereon and also operating to guide the runner in its forward 100 movement. When each movable runner reaches its rearward limit, it is of course elevated and moved forwardly by the action of the cranks; but the weight of the movable runner tends to sag the springs, and to overcome this sagging of the springs each movable member is provided with a pair of anti-friction-rollers 18, mounted upon horizontal axes between the movable runner and the 105 fixed runner, there being inclined tracks or 110

cams 19 fixed upon the adjacent side of the stationary runner and in the paths of the forward movements of the respective antifriction-rollers 18, whereby said tracks or cams 5 operate to elevate the movable runner and maintain the same in an elevated position independently of the support of the springs, the latter operating merely to move the runner forwardly when said runner is supported 10 upon the tracks or cams. At the end of the forward movement of the movable runner the rollers of course run off of the cams in order that the moving runners may gravitate into engagement with the roadway, and as 15 said movable runners are forced rearwardly the sled will be pushed forwardly upon its stationary runners. To prevent tilting of the movable runners, other antifriction-rollers 18^a are provided upon the outer sides of 20 the runners for engagement with the respective tracks or cams 19^a, carried by frame members or hangers 28, which depend from upper substantially horizontal frame-bars 29, which are connected at their ends by means 25 of converged braces 30, connected to the sides of the respective end portions of the stationary runner 2. The rollers 18^a coöperate with the cams or tracks 19^a in the same manner as and simultaneously with the rollers 18 when engaging the tracks 19. In addition to having bearings upon the fixed runners 2 each of the shafts 6 and 7 also has bearings upon the frame-bars 29, as clearly indicated in Fig. 3 of the drawings. It is 30 also proposed to brace each of the spring links or bars 14 by means of a bowed spring 31, having its lower end connected to the top of the movable runner 5, with its upper free end engaging the under side of the link to 35 take some of the strains thereon.

Motion is imparted to the shafts 6 and 7 by means of a motor of any preferred character mounted at any desired point upon the bed or platform 1, such a motor being indicated at 20, and provided with a drive-shaft 45 21, having a gear 22, preferably a sprocket, over which runs an endless sprocket-chain 23, engaging sprockets 24 and 25 upon the shafts 6 and 7. The bed or platform 1 is of 50 course provided with openings 26 and 27 to accommodate the sprocket-chain and the sprockets 24 and 25. When, as indicated in the accompanying drawings, the bed or platform would interfere with the cranks said bed or platform is of course provided with 55 openings to accommodate the cranks.

From the foregoing description it will be seen that the propelling or traction mechanism of the present invention is very simple 60 and effective for the purpose designed and may be mounted upon any ordinary sleigh which includes fixed rear runners and a bob or movable runners for steering the sleigh.

By reason of the disposition of the cranks of 65 the two shafts 6 and 7 the movable runners

are given a stepping movement, with the adjacent movable runners moving alternately in opposite directions, thereby to engage the road-bed at their forward limits and advance the sled by a pushing movement as the runners are moved rearwardly by the motor. By reason of the springs 14, which connect the moving runners with the cranks, said runners and the operating mechanism are cushioned when the moving runners strike the 70 road-bed and are also capable of yielding upwardly should they strike an obstruction in the road-bed when moving forwardly. This yieldable mounting of the movable runners is a very important feature of the present invention, as it obviates damage to the traction mechanism. When the runners are traveling rearwardly, the antifriction-rollers thereof of course travel beneath the tracks or cams, whereby the movable runners are 80 held against upward yielding when acting upon the roadway to advance the sled.

Having fully described the invention, what is claimed is—

1. In a traction-sled, the combination with 90 a frame supported on fixed runners, of a crank-shaft, a movable runner, a spring-hanger connecting the crank and the movable runner, and means to drive the shaft.
2. In a traction-sled, the combination with 95 a runner-supported frame, of a crank-shaft, means to drive the shaft, a movable runner, a spring-hanger having one end connected to the runner and its opposite end connected to the crank, and a guard member carried by 100 the runner and loosely embracing the hanger.
3. In a traction-sled, the combination with 105 a frame supported on fixed runners, of a movable runner, a crank - shaft upon the frame, means to drive the shaft, a spring-hanger connecting the crank and the movable runner, a guideway, and means upon the movable runner to engage the guideway and support the movable runner in an elevated position when traveling forward. 110
4. In a traction-sled, the combination with 115 a frame having a fixed runner, of a movable runner working at one side of the fixed runner, means for working the movable runner back and forth, a cam-track carried by the fixed runner, and a guide member carried by the movable runner and working upon the track during the forward movement of the movable runner to elevate the same. 120
5. In a traction-sled, the combination with 125 a runner-supported frame, of a movable runner, a crank - shaft, means for driving the crank-shaft, a flexible hanger connected to the crank and the runner, a guide member carried by the runner, and a track located in the forward path of the guide member to elevate the movable runner during its forward movement.
6. In a traction-sled, the combination with 130 a frame having a pair of fixed runners, a pair

of shafts mounted transversely of the frame and provided with cranks respectively located at the inner and outer sides of the individual runners, the members of each pair of cranks being disposed at opposite sides of the adjacent shaft, means for simultaneously rotating the shafts in the same direction, movable runners working back and forth at opposite sides of the respective fixed runners, 5 spring-links having their forward ends connected to the respective movable runners and inclined upwardly and rearwardly therefrom with their upper ends pivotally connected to the adjacent cranks, looped guards carried 10 by the movable runners and loosely embracing the respective spring-links, antifriction guide-rollers carried by the movable runners and located between the latter and the respective fixed runners, and tracks carried 15 upon opposite sides of the fixed runners and located in the paths of the forward movements of the rollers to elevate the movable runners when moving forwardly.

7. In a traction-sled, the combination with 20 a frame supported on fixed runners, of a movable runner, a crank-shaft upon the frame, a spring-hanger connecting the movable runner and the crank, a guideway upon the fixed runner, and a guide carried by the 25 movable runner and working upon the upper side of the guideway to support the movable runner in an elevated position when moving forwardly, and running at the under side of

the guideway during the rearward movement of the runner to prevent elevation thereof. 35

8. In a traction-sled, the combination of fixed runners, movable runners working at opposite sides of each fixed runner, means for raising and lowering and at the same time working the movable runners back and forth, guide members carried by opposite sides of the movable runners, tracks carried 40 upon opposite sides of the fixed runners for co-operation with adjacent guides of the movable runners, and other tracks supported at 45 the outer sides of the movable runners in co-operative relation with the adjacent guides.

9. In a traction-sled, the combination with a fixed runner having a substantially horizontal frame extending around the top thereof, of, of movable runners working at opposite sides of the fixed runner, means to raise and lower and at the same time work the movable runners back and forth, tracks upon opposite sides of the fixed runner, tracks hung 50 from the frame at the outer sides of the movable runners, and guide members carried by opposite sides of the movable runners for engagement with the respective tracks. 55

In testimony that I claim the foregoing as 60 my own I have hereto affixed my signature in the presence of two witnesses.

JAMES McGILLIS.
